UNITED STATES PATENT OFFICE.

EDWARD G. ROWLEY, OF BELLEVILLE, NEW JERSEY, ASSIGNOR TO UNDERWOOD TYPEWRITER COMPANY, OF NEW YORK, N. Y., A CORPORATION OF DELAWARE.

STENCILING MACHINE.

Original application filed June 24, 1924, Serial No. 721,982. Divided and this application filed December 26, 1925. Serial No. 77,867.

This invention relates to duplicating machines, in which a perforated drum is covered with an ink-blanket, saturated with ink applied to the interior of the cylinder and overlaid with a stencil, between which and a pressure-roll the paper to be stenciled is passed.

A feature of the present invention, is the provision of a work-sheet supporting table 10 which is hinged to the frame of the machine and held, when extended in operative position, by a supporting bracket, all parts of which fold automatically within the confines of the frame upon raising the table alongside 15 the cylinder, thus presenting no impediment to the placement of a cover.

Another feature of the invention is the provision of a telescopic extension of the table which enables the table to accommodate sheets of various lengths. The extension is slidably engaged below the main portion and has lugs which contact with a rod fixed in the outer part of the main table, providing an effective alignment.

Still another feature of the invention is the provision of an angular guide for the work-sheets which is adjustably and removably engaged upon the work-sheet supporting table, the guide being provided with a cushioned under surface to prevent marring the smoothly finished surface of the table when moved thereover.

This application is a division of my co-pending application, Serial No. 721,982, filed 35 June 24, 1924.

Other features and advantages will hereinafter appear.

In the accompanying drawings,

Figure 1 is an end elevational view of the machine, looking from the right-hand end thereof, and indicating a cover as applied thereover in dot-and-dash lines.

Figure 2 is an end elevational view of the machine, showing the work-supporting table 45 in operative position, parts being broken away to disclose the structural features, and the cylinder supports being shown in dot-and-dash lines.

Figure 3 is a front view of the work-support table, showing the extension in cross-section and drawn to an enlarged scale.

Figure 4 is a cross-sectional view taken on

line 4—4 of Figure 2, and showing the work-table supporting bracket and the stops of the table extension.

In the embodiment shown, the machine will be seen to comprise a support frame consisting of front and rear base bars 10, rigidly connected with upright sides 11 and 12, respectively at the right and left hand side of the machine, these members being supported on feet 13 resting on any level surface. The raised portions of the frame side 12 converge to a central boss 14, bored to receive a fixed plug 15 on which is revolvably mounted a cylinder, generally designated by the numeral 16, in such manner as to be readily removed. The right-hand side frame 11 has diverging U-shaped upper elements on which are mounted revolvable 60 trundles or rolls 17, engaging the cylinder 16 on opposite sides above its center. A third trundle or roll 18, bearing on the cylinder at the bottom, is rotatably mounted on a screw 19, in a plane directly below the 65 center of the cylinder.

A bracket 20 having an extending handle 21 is held to the end of the cylinder head by radially extending lugs 32 and 33 integral with the ends of the bracket.

A gravity actuated stop or pawl 34 having arms 35 and 36 is pivoted on a shouldered screw 37, set in the frame side 11, the stop being normally at rest against a fixed pin 38, and provided with a handle 39. When the cylinder handle 21 is turned to bring the cam face of the lug 32 into contact with the arm 36, the stop will tilt upon its pivot, allowing the lug to pass, and then return by gravity to its normal position to intercept the lug 33, preventing further rotation of the cylinder in clockwise direction, until the stop has been released by its handle 39. When the cylinder is rotated in an operative, contrary direction, the lug 33 passes freely over the arm 35 and, striking the arm 36, tilts the stop, raising the arm 35 to engage the inner face of the lug 32 stopping the cylinder; however, if a slight momentary cessation of motion of the cylinder is made, such as is caused by recoil of the lug against the arm, the stop will return to its normal position, permitting further rotation of the handle and cylinder.

Carried by lugs 40 and 41 on the frame sides 11 and 12 are the narrow rearward extensions 42 of a paper-deflector 43, extending upwardly and to the front of the cylinder, the deflector being mainly supported on ledges 44, extending inward from the frame sides.

Below the deflector, and extending further toward the front, is a fixed paper-apron 45, supported on lugs 46, extending inwardly from the frame side and to which it is firmly secured.

Normally level with the paper-apron is a work-sheet support table 47, generally rectangular but reduced at its rear corners and formed with downwardly extending ears 48 through which pass pivot screws 49 to enter bosses on the inner surface of the frame sides; the lateral edges of the table 20 are bent downwardly at a right angle to form flanges 50, and rigidly connected to their inner sides are angle plates 51 spaced from the under surface of the table to guide and support a telescopic extension plate 52. 25 This extension plate is provided with a downturned flange 53 at its front edge and near its rear edge is sheared and bent to produce stops 54 to make contact with a rod 55, fixed in the flanges and angle plates 50 and 51 near the front of the main table 47, thus providing a collapsible table of unusually large area.

Extending in from the frame side 11 is a boss 56 drilled in register to receive a rod 35 57 on which is mounted a link 58 adjacent the boss 56, the free end of the link being offset and pivoted at 59 to a strut 60, in turn pivoted on a pin 61, fixed in one of the table flanges 50 to which it is held by a cotter 62. 40 The free end of the strut 60 is provided with a foot 63 bent at an angle to make a flat contact with the front frame-base bar 10 when the table is extended horizontally. To prevent the toggle-bracket, constituted 45 by the link and strut, from moving inward or toward the cylinder upon turning the table down, a projection 64 is formed on the end of the link 58, on its inner side, the same making contact with the under surface 50 of the adjacent angle plate 51, and maintaining the pivot 59 just slightly outward or in advance of a straight line between the pivotal axes of the rod 57 and pin 61.

A paper-gage 65, having a raised flange 55 66, is secured to adjusting strips 67 having angle elements 68 riveted to the flange 66 and clamped, when in adjustment on the table, by thumb-nuts 69 engaging threaded posts 70 fixed in the table, this gage and its 60 attached strips being provided with cushioning material 71 over their entire contacting surfaces to prevent abrading and damaging the finish of the table.

A pressure-roll 72 feeds the work-sheets 65 past the printing line and into a receiving

trough 73 pivoted at the rear of the machine, the trough being swung up to a folded position when the machine is not in use.

The pressure-roll 72 is of a soft elastic nature, and is mounted in the ends of arms 74 pivoted on the rod 57. The arms 74 are of such length as to locate the pressure-roll 72 directly below the axis of the cylinder 16.

Variations may be resorted to within the scope of the invention, and portions of the 75 improvements may be used without others.

Having thus described my invention, I claim:

1. In a duplicating machine, the combination with a frame, a stencil cylinder revolvable therein, a pressure roll, and a paper-apron fixed in the frame to deliver sheets between the cylinder and roll, of a paper-table hinged in the frame to swing from the level of the apron to rest on the cylinder, and a toggle bracket to support the table when in its operative position, said bracket operating automatically when the table is raised or lowered.

2. In a duplicating machine, the combination with a frame, a stencil cylinder revolvable therein, a pressure roll, and a paper-apron fixed in the frame to deliver sheets between the cylinder and roll, of a paper-table hinged in the frame to swing from the level of the apron to rest on the cylinder, and a bracket to support the table when in its operative position, said bracket folding automatically within the contour of the frame when the table is raised and assuming an operative position when the table is lowered.

3. In a duplicating machine, the combination with a frame, a stencil cylinder revolvable therein, a pressure roll, and a paper-apron fixed in the frame to deliver sheets between the cylinder and roll, of a paper-table hinged in the frame to swing from the level of the apron to rest on the cylinder, and a bracket comprising two elements attached respectively to the table and frame and to each other, the elements of said bracket moving automatically with the table into either a supporting position or to fold with it wholly within the contour of the frame.

4. In a duplicating machine, the combination with a frame, a stencil cylinder revolvable therein, a pressure roll, and a paper-apron fixed in the frame to deliver sheets between the cylinder and roll, of a paper-table hinged in the frame to swing from an operative position to a rest position against the cylinder, the table having flanged side edges, and a support bracket comprised of a strut pivoted to one of the table flanges at one end and having a foot to contact with the frame at the other end, and a link pivoted to the frame below the pivotal point of the table and to the strut, whereby both 130

strut and link are folded against the bottom of said table when the table is raised.

5. In a duplicating machine, the combination with a frame, a stencil cylinder revoluble therein, a pressure roll, and a paper-apron fixed in the frame to deliver sheets between the cylinder and roll, of a paper-table hinged in the frame to swing into either an operative or inoperative position, 10 and a toggle-support bracket comprised of a strut pivoted to the table and a link pivoted to the frame and connected with the strut, whereby the free end of the strut is held against the frame when the table is in an operative position and the strut folded when the table is in an inoperative position.

6. In a duplicating machine, the combination with a frame, a stencil cylinder revoluble therein, a pressure roll, and a paper-apron fixed in the frame to deliver sheets between the cylinder and roll, of a paper-table hinged in the frame to swing into either an operative or inoperative position, 20 a toggle-support bracket comprised of a strut pivoted to the table and a link pivoted to the frame and connected with the strut, whereby the free end of the strut is held against the frame when the table is in an operative position and the strut folded when the table is in an inoperative position, and means on the link to prevent the bracket from folding inwardly.

7. In a duplicating machine, the combination with a frame, a stencil cylinder revoluble therein, a pressure roll, and a paper-apron fixed in the frame to deliver sheets between the cylinder and roll, of a paper-table hinged in the frame to swing from an operative position to a rest position against the cylinder, the table having flanged side edges, a toggle-support bracket comprised of a strut pivoted to one of the table-flanges at one end and having a foot to contact with the frame at the other end and a link pivoted to the frame below the pivotal point of the table and to the strut, whereby both strut and link are folded against the bottom of said table when the table is raised, and a projection on the link to contact with the table when in rest position, said projection maintaining the pivotal connection between the link and strut outwardly beyond the plane of the axes of the other said pivotal connections of the strut and link.

8. In a duplicating machine, the combination with a frame and a stencil cylinder revoluble therein, of a paper-table hinged in the frame to swing into operative or inoperative positions relative to the cylinder, and a support for the table automatically extensible when the table is moved into an operative position and automatically foldable when the table is raised into an inoperative position.

9. In a duplicating machine, the combination with a frame, a stencil cylinder revoluble therein, and a work-support table to deliver sheets to the cylinder, said table having downturned lateral flanges, of a rod fixed to extend between the flanges near the front of the table, a plate slidable below said table, said plate having a downturned front flange, and integral projections near the rear of the plate to contact with said rod when the plate is drawn outwardly.

10. In a duplicating machine, the combination with a frame, a stencil cylinder revoluble therein, and a work-support table having its side edges flanged downwardly, of strips having a right angle cross-section fixed to the inner surfaces of the flanges, said strips being spaced from the under surface of the table, a plate telescopically slideable in the mentioned spaces, said plate extending from side to side of the table and having a downturned front edge, a rod secured at its ends in said strips and flanges near the front of the table, and lugs integral with the plate, near its rear edge, to contact with said rod when the plate is withdrawn its full limit.

11. In a duplicating machine, the combination with a frame, a stencil cylinder revoluble therein, and a work-support table hinged in the frame to swing into an operative or an inoperative position, said table having downturned flanges at its side edges, of right angled cross-sectioned strips secured permanently to said flanges, the upper element of the strips being spaced from the table, an extension plate telescopically engaged between said strips and table, means facilitating extraction of the plate, and means limiting its withdrawal, said plate automatically receding when the table is raised to an inoperative position.

EDWARD G. ROWLEY.
